CLAIM

The ornamental design for humidifier, as shown and described.

DESCRIPTION

FIG. 1 is a left, front, top perspective view of a humidifier showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is right elevation view thereof; and,

FIG. 7 is a left elevation view thereof.

The broken lines represent portions of the structure that form no part of the claim.
